TILTING TABLE FOR SHEET MILLS

Clarence L. Taylor, Youngstown, Ohio, assignor
to The Aetna-Standard Engineering Company,
Youngstown, Ohio, a corporation of Ohio

Application September 22, 1931, Serial No. 564,296

10 Claims. (Cl. 30—47)

This invention relating as indicated to tilting tables for sheet mills, has particular reference to a form of construction adapted to be placed in juxtaposition to a common form of rolling mill for the purpose of handling the sheets adjacent such mill.

As is well known to those familiar with the art, it is usual to provide a pair of tilting tables on opposite sides of the mill stand for the purpose of receiving the sheets as they are discharged from the mill and to return the same over the mill to the forward side thereof to receive an additional pass in the rolling operation. There are numerous characteristics which any form of tilting table construction should possess in order to efficiently perform the function for which the same has been designed.

It is among the objects of my invention to provide a form of tilting table construction of the 20 class described which shall be capable of efficiently performing all of the functions of such constructions. A further object of my invention is to provide a form of construction which shall be capable of being moved out of the way sufficiently 25 to permit ready access to the rolls of the mill for dressing, polishing, heating, etc., without materially disturbing the placement of such apparatus adjacent the mill.

Another object of my invention is to provide 30 a form of tilting table construction which, during its operation, receives the pack or sheet from the mill, automatically aligns the same with respect to the desired path of travel of such pack or sheet preparatory to reversing the direction 35 of travel thereof, and passing the same back over the mill to the receiving side of the rolls. Other objects of my invention will appear as the description proceeds.

To the accomplishment of the foregoing and 40 related ends, said invention, then, consists of the means hereinafter fully described and particularly pointed out in the claims.

The annexed drawings and the following description set forth in detail certain mechanism 45 embodying the invention, such disclosed means constituting, however, but one of various mechanical forms in which the principle of the invention may be used.

In said annexed drawings:

50 Fig. 1 is a side elevational view of a rolling mill showing the apparatus comprising my invention associated therewith; Fig. 2 is a plan view of a portion of the apparatus illustrated in Fig. 1; Fig. 3 is an enlarged plan view of the tilting 55 table portion of the structure illustrated in Fig. 2;

Fig. 4 is a fragmentary side elevational view of the table structure illustrated in the previous figures showing in detail the means for oscillatably supporting the same; Fig. 5 is a fragmentary transverse sectional view of the apparatus illustrated in Fig. 2 taken on a plane substantially indicated by the line 5—5; Fig. 6 is a transverse sectional view of the apparatus illustrated in Fig. 3 taken on a plane substantially indicated by the line 6—6; Fig. 7 is a fragmentary sectional view of a portion of the tilting table construction illustrated in the previous figures showing in detail the actuating mechanism for the side guides thereof, said figure as arranged on the drawings being a bottom view partially in section of a portion of the apparatus as it is illustrated in Figure 3; and Figure 8 is a side elevation of the lever arm and its associated cam for actuating the side guides on the tilting table.

Referring now more specifically to the drawings, 75 and more especially to Fig. 1, the apparatus presently to be described and comprising my invention is shown associated with a rolling mill generally indicated at 1 which consists of a housing 2, an upper roll 3 and a lower roll 4. It will be 80 noted that in this figure the mill is of the two-high type, it being understood, however, that the apparatus comprising my invention may be employed with a mill having any of the usual number of rolls.

Referring now more particularly to Figs. 1 and 2, it will be noted that the apparatus comprising my invention is supported on a suitable base 5 which may be carried by beams 6 positioned adjacent the mill, such beams preferably being positioned adjacent a pit 7 into which one end of the tilting table presently to be described may swing.

The base 5 has mounted thereon a motor 8 which is of the usual design and which may have an electro-magnetic brake 9 associated therewith for the purpose for which such brakes are usually designed. Similarly mounted on the base 5 is a gear reduction unit generally indicated at 10 which includes a gear 11 which meshes with and is driven by a pinion 12 secured to and driven by the armature shaft of the motor 8. The shaft supporting the gear 11 has a crank arm 13 associated therewith which, upon rotation of the gear 11, will cause a reciprocation of a connecting rod 14. The connecting rod 14 is at its opposite 105 end, in the manner hereinafter more fully explained, removably secured to means associated with the tilting table for the purpose of reciprocating the same.

The tilting table proper, which is actuated by 110

the connecting rod 14, consists of a frame 15 which is mounted on a hollow shaft 16 and thereby pivotally supported in suitable bearings 17 and 18 carried by a bracket 19 forming a portion 5 of the base 5 of the apparatus. The frame member 15 has longitudinally extending substantially parallel channel-shaped members 20 associated therewith which are intermediately of their ends cross-braced by members such as 21. Rotatably supported at opposite ends of the side frame members 20 and extending transversely thereof are shafts 22 and 23, the former each carrying a pair of axially spaced sprocket wheels 24 about which endless conveyor chains 25 are trained. 10 The conveyor chains 25 are provided with rollers 26, which, bearing on tracks 27 provided therefor, support the chain in its travel about the table. It will be noted from Figs. 5 and 6 that the upper runs of the chains 25 are carried in 15 channel-shaped members 28 secured to the upper leg of the channel-shaped side frame members 20 and the lower runs of such chains are carried in the lower leg of such channel members.

The shaft 23 carrying one pair of sprockets 24 at one end of the table also carries a driving sprocket 29 about which is trained a driving chain 30. The chain 30 is driven by the apparatus which will now be described.

The base 5, as most clearly illustrated in Figs. 30 2 and 5, carries a second motor 31 which is of the usual design and which is, through the medium of a coupling 32, connected to a shaft 33 which extends axially of the hollow shaft 16 upon which the tilting table is supported. The shaft 33 at 35 its opposite end 34 is supported in suitable bearings 35 carried by a housing member 36. The housing member 36 is at its inner end provided with a radially extending annular flange 37 which is engaged and supported by a complementary removable portion 38 carried by the frame 15 of the table. The member 38 is preferably split in half to facilitate the assembly of the apparatus. The housing 36 carries a depending portion 39 in which is mounted a shaft 40 on which is journalled a gear 42 having an extended boss 41 with bearings 42'. The gear 42 meshes with a pinion 43 keyed to the drive shaft 33 and a sprocket wheel 44 is keyed to the extension 41 of the gear 42. A chain 30 is trained about the sprocket 45 wheels 29 and 44. A suitable aperture is of course provided in the housing 36 to permit the chain 30 to move about the sprocket 44.

The housing 36 is provided with a projecting arm 45 which is engaged by a screw 46 carried in 55 a bracket 47 which is secured rigidly with respect to the frame 15 of the table. The screw 46 is provided for the purpose of moving the arm 45 relatively to the bracket 47 so that the housing 36 is rotated about the axis of the shaft 33. Rotation of the housing 36, which is made possible by virtue of the fact that it is supported by the complementary annular flanged members 37 and 38, permits the proper adjustment of the distance between the centers of the sprockets 29 and 44 60 to compensate for differences in length of the chain 30.

The frame 15 forming a portion of the tilting table has a depending bracket 48 which rotatably supports a stub shaft 49. The stub shaft 49 is 70 terminally provided with a coniform gudgeon 50 adapted to receive the coniform bearing 51 carried by the terminal of the connecting arm 14. The axis of the gudgeon 50 is eccentric with respect to the axis of the shaft 49 so that as the shaft is rotated the position of the tilting table

with respect to the mill may be accurately adjusted. Rotation of the shaft 49 is effected by means of a pinion 52 carried by such shaft which meshes with a worm screw 53 rotatably supported in the bracket 48.

The crank arm 14 is removably secured to the gudgeon 50 by means of a plate 51 which is oscillatably supported on a stub shaft 55 carried by the bracket 48. The plate 54, as most clearly illustrated in Fig. 4, is provided with a manipulating handle 56 by means of which the same may be rotated about the shaft 55 into and out of engagement with the bearing 51 and the gudgeon 50. The casing around the gudgeon 50 is at its lower portion provided with a groove 57 into which a lip 58 on the edge of the plate 54 moves to laterally support the lower edge of such plate. The plate 54 also carries a cam projection 59 adapted to be engaged by a latch 60 which is pivotally mounted on a pin 61 carried by the bracket 48. This latch is provided for the purpose of maintaining the plate 51 in the dotted line position generally indicated at 62 in Fig. 4. When the plate 54 is moved to the dotted line position 62, then the connecting rod 14 may be 100 moved axially off from the gudgeon 50 and permitted to rest on a bracket 63 provided therefor on the edge of the base 5. When the arm 14 is so disconnected, then the entire tilting table may be swung into the substantially vertical position indicated by dotted lines at 64 in Fig. 1 without disturbing any of the rest of the table actuating mechanism.

The tilting table previously described is provided with side boards or guides 65 and 66, most 110 clearly illustrated in Figs. 5 and 6. The side guides 65 and 66 are preferably in channel form and arranged back to back and are respectively supported by means of arms 67 and 68.

Extending longitudinally of the table, as most 115 clearly illustrated in Fig. 3, and journalled in the cross brace members 21, are shafts 69 and 70. The shaft 69 has keyed thereto crank arm 71 and rotatably supports crank arm 72, which arms are respectively oscillatably secured at their opposite ends to guide supporting arms 67 and 68, and the shaft 70 has keyed thereto crank arm 74 and rotatably supports crank arm 73, such arms being respectively oscillatably secured at their opposite ends to guide supporting arms 68 125 and 67.

The shafts 69 and 70 have also keyed thereto crank arms 75 and 76 respectively, which are interconnected by means of a link 77. A retractile spring 78 is at its opposite ends secured to 130 arms 71' and 74' for the purpose hereinafter more fully explained.

From the above description it will be noted that upon rotation of one of the shafts 69 or 70 a rotation of the crank arms keyed thereto will be 135 effected accordingly and these crank arms will respectively cause a lateral movement of the side guides 65 and 66 relatively to the side frame members 20. The spring 78 normally urges the side guides 65 and 66 toward each other and into engagement with the sides of the sheet or pack carried on the table by the chains 26.

Actuation of the side guides 65 and 66 may be effected manually by simply pulling laterally on one or the other of these guides. The crank arms 145 by which the guides are supported on the shafts 69 and 70 and the links which interconnect such shafts will, when one guide is moved laterally, cause an equal and opposite movement of the other guide. During the normal operation of the 150

above described apparatus, as the table is tilted from the receiving to the discharging position the side guides will be actuated by the mechanism most clearly illustrated in Figs. 3 and 7.

5 Referring now more specifically to these Figs. it will be noted that one of the shafts, particularly shaft 69, has a collar 79 slidably keyed thereto, which collar may be actuated by means of a hand lever 80 pivotally supported intermediate of its ends on a bracket 81 and projecting laterally in a handle 82 from the side of the table.

10 The collar 79 is one portion of a clutch generally indicated at 83, the other member 84 of which is rotatably supported by means of a bearing 85 on the shaft 69 and carries a bevel gear 86. The bevel gear 86 is in mesh with a segmental bevel pinion 87 which is keyed to a shaft 89 rotatably supported transversely of the table. The shaft 89 at one outer end 90 has keyed thereto an arm 91 which terminally carries a cam roller 92 mounted on a shaft 93.

15 The cam roller 92, as most clearly illustrated in Fig. 1, rides on the surface of a cam 94, which is supported on a suitable bracket carried by the frame 5 of the machine. The cam 94 has high points 95 and 96 and an intermediate low point 97. When the lever 82 is moved so as to effect driving communication between the collar 79 and the bevel gear 86, and accordingly between the shaft 30 69 and the arm 91, the spring 78 urging the guides 65 and 66 toward each other will likewise urge a rotation of the shaft 69 and accordingly likewise the shaft 70 to thus force the roller carried by the arm 91 on to the cam 94.

20 35 The operation of the above form of tilting table construction may be briefly described as follows:

40 As most clearly illustrated in Fig. 1, a separate tilting table will preferably be employed on each side of the mill 1. Considering now that the rotation of the rolls 3 and 4 is as indicated by the arrows on Fig. 1, the table positioned at the left side of the mill will be for the purpose of receiving the pack or sheet and feeding the same into the bite of the rolls, and the table on the right side of the mill will be for the purpose of receiving the rolled sheet or pack and if the same has not as yet reached the desired length, return the same to the front side of the mill for the subsequent pass. The two tables will be electrically interconnected so as to simultaneously move from the full lined position illustrated in Fig. 1 to the dotted line inclined position illustrated in the same figure. The oscillation of the tables which 45 occurs about the axis of the shafts 16 and 33 is effected by the motors 8 driving the gears 11 which in turn cause a rotation of the cranks 13 and accordingly a reciprocation of the connecting arms 14. Suitable limit switches will be provided 50 which will cause energization and de-energization of the motors 8 so as to properly govern the limits of travel of the ends of the table which are presented to the working rolls of the mill. The electromagnetic brakes 9 associated with the 55 motors 8 likewise assist in bringing the table to rest at the proper position. As previously indicated, the tables may be adjusted relatively to the mill by means of the adjusting screws 53 which afford a micrometer adjustment which 60 might not be capable of attainment by shortening or lengthening the connecting rods 14 although this latter expedient may be employed for the purpose of effecting coarse adjustments of the table with respect to the mill.

75 Inasmuch as the chains 26 which support the

sheets or packs on the table must move such sheets or packs on to and off from the table at the same end, the direction of rotation of the armature of the motor 31 must of course be reversed to effect such reversals of direction of movement of the sheet or pack engaging portions of the chain 26.

80 The operation of the means for manipulating the side guides 65 and 66 is briefly as follows:

85 Considering for instance the table positioned at the right of the mill, as illustrated in Fig. 1, when such table is in the full line position, i. e., in position to receive a sheet or pack which will be passed through the rolls 3 and 4 by means of the table on the opposite side of the mill, the cam roller 92 will ride on the high part of the cam 94. This means that the arm 91 has been rotated sufficiently to cause a rotation of the shaft 69 to effect a separation of the side guides 65 and 66. The distance between the guides 65 and 66 may be adjusted by de-clutching the collar 79 and the pinion 86 and then adjusting the guides to the desired distance before the clutch is again engaged.

90 100 After the sheet or pack has been discharged from the rolls 3 and 4 and moved back onto the table at the right side of the mill, a suitable limit switch will cause an energization of the motor 8 to move the table to the dotted inclined position preparatory to moving the sheet or pack across the mill to the front side thereof. As the table moves through the horizontal position on its way to the upwardly inclined position, the cam roller 92 will ride into the depression 97 on the cam 94 permitting the spring 78 to pull the guides 65 and 105 66 together and into engagement with the sides of the sheet or pack on the table. This inward movement of the guides centers the pack on the table and simultaneously aligns the same so that it will pass back over the top roll without striking 110 the side of the housings.

115 120 As the table moves from the horizontal to the dotted inclined position, the roller 92 will again ride up onto the high point 96 of the cam 94 so that the guides 65 and 66 will be spread apart to permit the sheet or pack on the table to pass freely over to the forward side of the mill.

125 After the pack or sheet is moved to the front side of the mill the table at the left of the mill will be depressed to present such sheet or pack to the bite of the rolls for a subsequent rolling pass.

130 As previously indicated, one of the desirable features of the described form of tilting table construction is that the supporting means for the table, as most clearly illustrated in Fig. 1, i. e., the base 5 and its associated mechanism, is disposed entirely along one side of the table so that the tilting portion of the apparatus may be easily moved into a substantially vertical 135 position, as illustrated at 64 in Fig. 1, to permit ready access to the rolls 3 and 4 of the mill for the purpose of polishing and heating the same so that these operations may be carried on without materially disturbing the tilting table construction. The entire mechanism may be readily picked up and moved into and out of position on the supporting beams 6 by crane chains secured to arms 98 which preferably project from the corners of the base 5.

140 145 A further description of the apparatus comprising my invention is believed unnecessary for those familiar with the art. A number of the details of the construction of my apparatus have not been shown or described in minute detail 150

for the reason that it is believed the construction and operation of such details are sufficiently familiar to those versed in the art so that it is not necessary to further complicate the illustration and description of my invention.

Other modes of applying the principle of my invention may be employed instead of the one explained, change being made as regards the mechanism herein disclosed, provided the means stated by any of the following claims or the equivalent of such stated means be employed.

I, therefore, particularly point out and distinctly claim as my invention:

1. In a tilting table, the combination of a frame supported for oscillation about an axis extending transversely of the table, shafts on opposite ends of said frame, sprockets on said shafts, conveyor chains trained about said sprockets, a driven shaft concentric with the axis of oscillation of said table, a housing member about one end of said shaft, a shaft supported by said housing, meshing gears on said shafts, means for adjustably supporting said housing relatively to said frame, and means drivably connecting said last named shaft and said conveyor chains.

2. A tilting table for use with rolling mills, comprising a supporting base, a frame arranged substantially entirely on one side of said base and entirely supported thereby for oscillation about an axis extending transversely of said frame, a reversible conveyor on said frame, and means supported entirely on said base for driving said conveyor.

3. A tilting table for use with rolling mills, comprising a supporting base, a frame arranged substantially entirely on one side of said base and entirely supported thereby for oscillation about an axis extending transversely of said frame, a reversible conveyor on said frame, and means supported entirely on said base for oscillating said table.

4. A tilting table for use with rolling mills, comprising a supporting base, a frame arranged substantially entirely on one side of said base and entirely supported thereby for oscillation about an axis extending transversely of said frame, a reversible conveyor on said frame, and means supported entirely on said base for oscillating said conveyor and driving said conveyor.

5. A tilting table for use with rolling mills, comprising a supporting base, a frame supported entirely on said base for oscillation about an axis extending transversely thereof, said frame arranged substantially entirely on one side of said base whereby said frame may be moved to a substantially vertical position, a reversible conveyor on said frame, and means supported entirely on said base for driving said conveyor.

6. A tilting table for use with rolling mills, comprising a supporting base, a frame supported entirely on said base for oscillation about an axis

extending transversely thereof, said frame arranged substantially entirely on one side of said base whereby said frame may be moved to a substantially vertical position, a reversible conveyor on said frame, and means supported entirely on said base for oscillating said frame.

7. A tilting table for use with rolling mills, comprising a supporting base, a frame supported entirely on said base for oscillation about an axis extending transversely thereof, said frame arranged substantially entirely on one side of said base whereby said frame may be moved to a substantially vertical position, a reversible conveyor on said frame, and means supported entirely on said base for oscillating said frame and driving said conveyor.

8. A tilting table for use with rolling mills, comprising a supporting base unit, a tiltable conveyor table supported on said base, relatively movable side guides associated with said conveyor table, means interconnecting said side guides whereby movement of one results in equal and opposite movement of the other, a guide actuating arm connected with said guide connecting means, a fixedly supported cam adapted to be engaged by said arm, and spring means urging said guides toward each other and said arm onto the face of said cam.

9. A tilting table for use with rolling mills, comprising a supporting base unit, a tiltable conveyor table supported on said base, relatively movable side guides associated with said conveyor table, links interconnecting said guides whereby said guides may be moved equally in opposite directions, an actuating arm connected with said links, a fixedly supported cam member, spring means urging said guides toward each other and said arm onto the face of said cam, and an adjustable connection between said arm and links whereby the distance between said guides may be determined for a given position of said arm on said cam face.

10. A tilting table for use with rolling mills, comprising a supporting base unit, a tiltable frame supported entirely on said base and at substantially entirely one side thereof, a reversible conveyor carried by said frame, means supported entirely on said base for oscillating said frame and driving said conveyor, relatively movable side guides supported on said frame adjacent opposite sides of said conveyor, links interconnecting said guides whereby movement of one of said guides moves the other equally in an opposite direction, an actuating arm connected with said links, a fixedly supported cam member so positioned that said arm will be moved over the face thereof as said frame is oscillated, and spring means urging said guides toward each other and said arm onto the face of said cam.

CLARENCE L. TAYLOR.
